UNITED STATES PATENT OFFICE.

HARLIN G. FARMER, OF GARNETT, KANSAS.

AEROPLANE.

Application filed August 30, 1921. Serial No. 496,839.

To all whom it may concern:

Be it known that I, HARLIN G. FARMER, a citizen of the United States, residing at Garnett, in the county of Anderson and 5 State of Kansas, have invented certain new and useful Improvements in an Aeroplane, of which the following is a specification.

This invention relates to aeroplanes, and has for one of its objects to increase the 10 stability and steadiness of devices of this character.

Another object of the invention is to provide a device of this character wherein provision is made for conserving the power of 15 the motor and utilizing the lifting power of the propeller to increase the efficiency and preventing the propeller from interfering with the currents through which the plane passes.

20 Another object of the invention is to provide a device of this character wherein the parts are arranged so that the motor and other heavy parts are disposed substantially at the center of gravity of the aeroplane 25 and thus conserve the movements.

With these and other objects in view and others which will be manifest and suggested as the nature and purpose of my invention are revealed in the following specification and drawing wherein I have shown a practical, yet preferred embodiment thereof.

In the accompanying drawings:

Figure 1 is a side elevation,

35 Fig. 2 is a plan view, and

Fig. 3 is a front elevation of the improved device.

Fig. 4 is a diagrammatic perspective view 40 illustrating the arrangement of the control of the steering devices.

The improved device comprises a supporting frame formed with vertical post members 10, horizontal brace or stay members 11, and obliquely directed brace wires 45 or rods 12, of the usual aeroplane construction.

A "floor" portion 13 connects the lower ends of the posts and supports an operator's seat 14. The floor 13 likewise supports a steering wheel 15 and winding drum 50 16, and the operating levers, one of which is indicated at 17, preferably operating over a toothed segment 18 of the usual construction, whereby the position of the 55 lever may be retained.

Landing wheels 19 of the usual construc-

tion are also preferably supported by the floor members 13, certain members of the latter being curved at the forward portion, as shown at 20, to facilitate the "landing" 60 of the plane.

A cupped plane or main wing member 21 is attached to the upper ends of the post members 10 and extends beyond the same at each end, and is supported by the usual 65 brace rods 22.

Hingedly coupled at 23 to the main wing member 21 and extending rearwardly therefrom is a supplemental wing or plane 24, preferably formed with a compound or reverse curve as shown in Fig. 1.

Extending rearwardly from the frame members 10 and from the frame of the plane 21, is another frame represented as a whole 75 at 25 and converging toward the rear and supporting the usual arrangement of steering wings 26.

Supported by the frame members 10 and 11 in any suitable manner is a motor, represented conventionally at 27, and arranged to 80 operate a propeller, represented conventionally at 28.

It will be noted that the motor is located beneath the rear portion of the main plane or wing 21 with the propeller operating as 85 close as possible to the under face of the wing, and nearer the rear than the front or forward edge of the main wing.

By this means the heavier portions of the plane, such as the motor and the weight of 90 the operator are located substantially at the center of gravity, so that a "balance" is produced, which materially increases the stability and steadiness.

The steering wings 26 are controlled by 95 the usual arrangement of pull cables or wires, indicated at 29, and leading to the winding drum 16, while the movable plane 24 is provided with suitable controlling wires or cables 30 leading over guide pulleys 100 31 and thence to the lever 17, as shown.

In the ordinary arrangement of the propeller relative to the wings or planes, or in advance of their forward lines, a relatively great amount of power is wasted by failing 105 to utilize the force of the lateral air currents produced by the propeller. With the arrangement shown however, with the propeller rearwardly of the forward line of the main or stationary plane 21, and operating 110 relatively close to its lower central surface, the lifting power of the air "cut" by the

propeller is utilized to assist in maintaining the aeroplane in the air and thereby materially increasing the buoyancy and rendering it much easier to control the movements. 6 It will be noted that the seat or the operator and the means for controlling the steering wings are located in advance of the line of the propeller, and also below the line of the same, thereby materially increasing the 10 steadiness and buoyancy.

The power necessary to drive the plane is also materially increased by the arrangement shown.

In the accompanying drawings, I have 15 illustrated my invention embodied in one form by way of example, and which in practice has been found to be highly satisfactory in obtaining the desired results. It will be obvious however that other embodiments 20 may be adapted, and that various changes in the details of construction may be resorted to by those skilled in the art without departing from the spirit and scope of the invention. It is furthermore understood 25 that the invention is not necessarily limited

or restricted to the precise elements shown except in so far as such limitations are specified in the subject matter being claimed.

Having thus described the invention, what is claimed as new is:

In an aeroplane a main supporting frame carrying controlling elements at the rear, a main sustaining plane above the frame at the front, a rear plane movably coupled to the main frame, a motor including a drive shaft and supported by the frame beneath the main sustaining plane, a propeller mounted on the main shaft of the motor and operating rearwardly of the forward line of the main plane and relatively close to the under surface of the same, and a seat for the operator supported on the main frame below the line of the propeller and in advance thereof, whereby the balance between the parts is effected and the equilibrium thereby maintained.

In testimony whereof, I affix my signature hereto.

HARLIN G. FARMER.
